(57) **CLAIM**

The ornamental design for the wine rack, as shown and described.

DESCRIPTION

FIG. 1 is a top perspective view of a wine rack showing my new design;

FIG. 2 is top view of the wine rack;

FIG. 3 is a bottom view of the wine rack;

FIG. 4 is a left side view of the wine rack;

FIG. 5, is a right side view of the wine rack;

FIG. 6, is a rear view of the wine rack; and,

FIG. 7, is a front view of the wine rack; and,

FIG. 8, is a close up perspective view of a portion of FIG. 1. Any broken lines illustrated in the drawings are directed to environmental structure and do not form part of the design sought to be patented.
